Specification for Design.

Patented Jan. 7, 1913.

Application filed September 23, 1912. Serial No. 721,986. Term of patent 7 years.

To all whom it may concern:

Be it known that I, CHARLES F. HUMPHREYS, a subject of George V, King of Great Britain, and a resident of Lancaster, in the county of Lancaster and State of Pennsylvania, have invented a new, original, and ornamental Design for Linoleum, Oil-Cloth, or Floor-Covering, of which the following is a full, clear, and exact description, reference being had to the accompanying drawing, forming part of this specification.

The figure is a plan view of a piece of linoleum embodying my design.

I claim:

The ornamental design for linoleum, oil-cloth or floor covering as shown.

CHARLES F. HUMPHREYS.
